United States Patent [19]

Kudoh et al.

[11] Patent Number: Des. 298,231

[45] Date of Patent: ** Oct. 25, 1988

[54] LEAD FRAME FOR A SEMICONDUCTOR ELEMENT OR THE LIKE

[75] Inventors: Kazunao Kudoh; Hitoshi Akazawa, both of Hyogo, Japan

[73] Assignee: Sumitomo Electric Industries, Ltd., Osaka, Japan

[**] Term: 14 Years

[21] Appl. No.: 726,737

[22] Filed: Apr. 24, 1985

CLAIM

The ornamental design for a lead frame for a semiconductor element or the like, as shown and described.

DESCRIPTION

FIG. 1 is a top plan view of a lead frame for a semiconductor element or the like showing our new design, the bottom being a mirror image thereof;

FIG. 2 is a right side elevational view thereof, the opposite side being a mirror image thereof; and

FIG. 3 is a front elevational view thereof, the rear being a mirror image thereof.
